UNITED STATES PATENT OFFICE.

EMERY J. WILSON, OF CLEVELAND, OHIO.

CLUTCH.

1,249,704.

Specification of Letters Patent. Patented Dec. 11, 1917.

Application filed August 21, 1913. Serial No. 785,827.

To all whom it may concern:

Be it known that I, EMERY J. WILSON, a citizen of the United States, residing at Cleveland, in the county of Cuyahoga and State of Ohio, have invented certain new and useful Improvements in Clutches, of which the following is a specification.

This invention relates to improvements in clutches generally and particularly to those 10 of the band type.

More specifically the invention relates to clutching mechanism adapted to be arranged between a driving gear and a drum and consisting of a clutch band adapted to be tightened by suitable levers which are operated from an operating arm adapted to be in turn operated from roller bearing mechanism arranged between the arm and a spring pressed lever, the arrangement of 20 the parts being such that the roller bearing member may assume a position for operating the arm in one direction to release the band and may be moved into another position to cause the same tendency of the spring 25 pressed lever to shift the arm and set the band.

The invention may be further briefly summarized as consisting in the construction and combination of parts hereinafter set forth 30 in the following description, drawings and claims.

Referring to the drawings, Figure 1 is a side elevation of a portion of a gear wheel showing the device applied; Fig. 2 is a vertical section on the line A—A, Fig. 1, through the center of the device showing some of the parts in elevation; Fig. 3 is a detail view, and Fig. 4 is a sectional plan view on the line B—B, showing certain of 40 the operating levers.

In carrying out the invention any preferred form and construction of parts may be employed so long as they possess the necessary characteristics, but I have shown 45 one arrangement in the drawings which is effective in operation, and in this embodiment 1 represents the driving shaft which has keyed to it a gear 2. Loosely mounted on the shaft 1 is a drum 3 to be driven from 50 the gear 2. These parts are of any preferred construction and form no part of the invention except in so far as they enter the combination.

rigid with the gear and preferably forming 55 a part thereof is a pair of bracket members 4, one on each side of the web of the

gear 2 which support trunnions 5 of the rocker member 6. This rocker member is provided with ears 7 which receive a pin 8 passing through the loops in the end of a clutch band 9 which is provided with the usual asbestos or other facing 10 for engagement with the periphery of the drum 3. At a suitable angle with respect to the ears 7 this rocker member 6 is provided with an 65 operating arm 11 pivotally connected to a link 12 for a purpose to be described.

Mounted in the brackets 4 are trunnions 13 of a light end pull rocker member 14 provided with a crank arm 15 shown partially 70 in full and dotted lines in Fig. 1, and connected in the eye of a bar 16 threaded into a suitable turn buckle 17. This turn buckle is threaded onto the end of a bar 18 secured to the other end of the clutch band 75 9. Forming a part of the light end pull rocker member 14 is a clutch tightening arm 19 provided with a straight lower edge 20 extending on both sides of the radius drawn from the center of the tightening rocker 80 member at right angles to the edge 20. Mounted in this tightening arm 19 is a pin 21 pivotally connected to the link 12 at a point such that there is a differential 85 movement of the parts and there is a sort of lifting action conveyed to the light end pull rocker member 19 through the lever 11.

Secured to an ear 22 formed on the inner periphery of the gear is an energizing lever 23 having a straight face 24 coextensive 90 with the face 20 and adapted to be substantially parallel with respect thereto when the clutch is set. Secured to this lever preferably intermediate its ends, is a connection 25 having a shank 26 extending 95 down through a boss 27 forming a part of the gear. This shank receives a compression spring 28 arranged between the boss and a washer 29 held in position by a nut 30. Arranged between the edge 24 of the energizing lever and the edge 20 of the 100 tightening arm is a cross head 31 carrying a pair of rollers 32 and 33 which roll one against the other and against the edges 20 and 24. This cross head member is secured 105 to a rod 34 pivotally connected to an operating lever 35 pivoted upon a pin 36 supported in the web of the gear. This lever 35 is connected by a suitable link 37 to one arm of a bell crank lever 38. The other 110 arm 39 of this lever is connected by a link 40 to a sliding sleeve 41 slidably mounted

upon the shaft 1. I prefer to key the bell crank lever 38 to an upright shaft 42 mounted in the boss of the gear and to provide a lever 43 at the upper end and connected by a link 44 with the sleeve 41. Any suitable mechanism may be provided for shifting the sleeve 41.

In operation, assuming that the parts are in the position shown in Fig. 1, when the clutch is set and that the operator wishes to release the clutch, the clutch sleeve 41 is shifted to the right, as shown in Fig. 2, with the result that the lever 35 is moved to the left, as shown in Fig. 1, when the cross head with the rollers 32 and 33 will be moved to the left until they pass beyond the perpendicular extending from the edge 20 to the center of the pivot 13, when the force of the spring 28 through the lever 23 will cause the tightening arm to operate in a clockwise direction, with the result that the crank arm 15 will tend to loosen the band when the gear will rotate free of the drum. When the clutch is to be set, the parts are operated in a reverse direction and the cross head is moved to any desired point along the edges 20 and 24 with the result that the lever ratio between the energizing device and the tightening arm is varied to the proper extent to meet the required conditions.

The arrangement of the differential mechanism is such that the pull on the band 9 caused by the rotating gear and the frictional drag of the drum tends to give the lever 11 a counter clockwise movement, with the result that the link 12 pulls upon the arm 19 tending to give it a counter-clockwise movement also. In this way the heavy end pull assists the light end pull, and the action of the energizing device.

Having described my invention, I claim:—

1. In a clutch, a driving element, a driven element, and clutching mechanism between said elements comprising a clutching device, operating means therefor, an energizing device fixed against bodily movement, and means between said energizing device and the clutch operating means for causing the former to exert its force either to release the clutch or to set it.

2. In a clutch, a driving element, a driven element, and clutching mechanism between said elements comprising a clutching device, operating mechanism therefor, an energizing device fixed against bodily movement, and means for varying the effect of the energizing device upon the operating mechanism in either the setting or releasing operation.

3. In a clutch, a driving element, a driven element, and clutching mechanism between said elements comprising a clutching device, operating mechanism therefor, an energizing device coöperating with the operat-

ing mechanism to actuate the clutch, said energizing device being fixed against bodily movement, and means for varying the effect of the energizing device on the operating mechanism.

4. The combination with a drum, of a band coöperating therewith, operating mechanism for setting and releasing the band upon said drum, an energizing device, and means between the operating mechanism and the energizing device for causing the latter to exert its force either to set or release the band.

5. The combination with a drum, of a band coöperating therewith, operating mechanism for setting and releasing the band upon said drum, an energizing device, and means for varying the effect of the energizing device on the operating mechanism in either the setting or releasing operation.

6. In a clutch, a driving element, a driven element, and clutching mechanism between said elements comprising a clutching device, operating means therefor including an operating arm, an energizing device fixed against bodily movement, and means between the energizing device and the operating arm for transmitting the force of the energizing device to the operating arm for either the release or the setting operation.

7. In a clutch, a driving element, a driven element, and clutching mechanism between said elements comprising a clutching device, operating means therefor including an operating arm, an energizing device fixed against bodily movement, and a movable member arranged between the operating arm and the energizing device for varying the effective length of the operating arm.

8. In a clutch, a driving element, a driven element, and clutching mechanism between said elements comprising a clutching device, operating means therefor including an operating arm, a lever, means normally tending to move said lever said means being fixed against bodily movement, and means for transmitting the force of said lever to the operating arm and for varying the lever ratio between the two.

9. In a clutch, a driving element, a driven element, and clutching mechanism between said elements comprising a clutching device, operating means therefor including an operating arm, a lever, means normally tending to move said lever, a cross head arranged between said arm and said lever and adapted to vary the lever ratios between the two for both the release and the setting operation, and means for operating said cross head.

10. In a clutch, a driving element, a driven element, and clutching mechanism between said elements comprising a clutching device, operating means therefor including an operating arm, a spring actuated

lever, a roller bearing cross head arranged between said arm and said spring pressed lever and adapted to vary the lever ratios between the two for both the release and the setting operation, and means for operating said roller bearing cross head.

11. In a clutch, a driving element, a driven element, and clutch mechanism between said elements comprising a clutching device, differential operating mechanism between the same comprising a rocker arm for the light end pull, a rocker arm for the heavy end pull, suitable connections between said rocker arms whereby the pull on the rocker arm for the heavy end pull will as-

sist in the operation of the rocker arm for the light end pull in the setting operation, and means for actuating said differential operating mechanism and consisting of an operating lever arm, an energizing device, 20 and means arranged between the operating lever arm and the energizing device for varying the lever ratio in the setting operation.

In testimony whereof I affix my signature 25 in presence of two witnesses as follows:
